UNITED STATES PATENT OFFICE.

JOHN GROH, OF CHICAGO, ILLINOIS.

PIPE-CLEANING MACHINE.

1,313,850.

Specification of Letters Patent. Patented Aug. 19, 1919.

Application filed March 20, 1919. Serial No. 283,737.

To all whom it may concern:

Be it known that I, JOHN GROH, a citizen of the United States, residing at Chicago, in the county of Cook and State of Illinois, 5 have invented certain new and useful Improvements in Pipe-Cleaning Machines, of which the following is a specification.

This invention relates to a machine adapted to act upon pipes, tubes, flues, etc., to 10 clean off and polish their exterior surfaces.

In the construction of mechanism for this purpose, it has been my aim above all to provide means for removing, disengaging, or grinding off the formation of rust, dirt, 15 scale, etc., in an effective manner without injuriously affecting the body of the pipe under treatment, and without mutilating or breaking down such threads as may be formed upon the pipe; and in accomplishing these ends to employ a device that is 20 essentially simple and inexpensive both in construction and operation. It has, furthermore, been an object of this invention to utilize a mechanism that, because of its simplicity, is of relatively light weight and 25 hence easily portable, so that it may be operated in places where greater advantage and convenience is to be gained by bringing the machine to the material that is to undergo treatment, rather than vice-versa. 30

With these and other objects in view, I will now refer to the accompanying drawing in which is exhibited a preferred embodiment of the principal parts of this invention, Figure 1 being an end elevation, 35 Fig. 2 a side elevation, and Fig. 3 an enlarged fragmentary detail in cross section taken on line 3—3 of Fig. 1.

As shown in the drawing, use is made of a 40 frame which may conveniently be set up on any suitable support, the frame comprising companion arms 5, each flanged at its lower end as at 6 to receive a bolt 7 that secures the device in place. Guides 8 are provided 45 on each arm as shown, and supported by the upper ends of the arms is a cross head 9 through which extends a screw shaft 10 operable, if desired, by a hand wheel 11. Arranged to slide vertically upon the guides 50 is a box 12 constituting a journal for a rotatable shaft 13 which may be driven by power applied in any suitable manner, the box having a swivel connection with the screw shaft 10 by which its vertical position 55 within the frame may be adjusted.

Mounted adjacent the front side of the

frame is a block 14 having thereon a transverse channel for the reception of a U-shaped journal box 15 which is removably secured in place. This journal box carries 60 two freely rotatable companion rollers 16 which are in coöperative relation with a third roller 17, which is locked to the driving shaft 13 by any approved means. The pipe to be treated, designated as 18, is arranged for longitudinal travel between these three rollers in the direction of the arrow, it being understood that some sort of a support is provided for the pipe ends during its movement through the machine. 70

I will now describe in detail the construction and arrangement of the three rollers—the upper one having driving and two lower ones driven relation—as this represents one of the important and novel improvements 75 of this invention. First of all, it is to be noted that the axes of the several rollers are parallel, and that each roller is provided with certain circumferential grooves or channels, their interrelation being best 80 shown in Fig. 3. I prefer that the grooves in each roller shall be two in number, with their sides square cut, the grooves in the driving or upper roller being denoted as A and B, while those on the driven or lower 85 rollers are denoted as C and D, the uncut portions of each roller periphery constituting ribs or flanges whose acting surfaces are secured in the machine with the driven rollers 90 in a coincident plane slightly ahead of the driving roller 17, by which arrangement the driven rollers are the first to engage the pipe; and in the preferred construction the forward end of the driving 95 roller lies approximately midway of the width of the front groove C in the driven rollers, while the rear end of the driven 100 rollers lies approximately midway of the width of the rear groove B of the driving 105 roller.

In the operation of the machine, the pipe to be treated is placed upon the lower rollers 16 and the hand wheel operated to adjust the upper or driving roller upon the pipe 110 with the desired pressure. The power is then applied to drive the upper roller 17,

and this results in the pipe also being revolved; at the same time it causes the pipe to travel lengthwise through the machine. The driven rollers first act upon the pipe to disengage therefrom the rust or other foreign matter and generally, to clean up the surface, while the driving roller performs a grinding and polishing action. The travel of the pipe is caused more perceptibly by the upper roller, although the formation and interrelationship of all the rollers is necessary to this action. The propulsion of the pipe may be attributed to the use of properly formed rollers, those below being slightly ahead, while the driving roller above is correspondingly behind, so as to exert what may be termed a tilting tendency upon the pipe, the resultant effect being that of traction such as to draw the pipe through the machine as it undergoes its treatment.

The machine which has been described in detail is manifestly simple both in its construction and operation. It embodies but few parts and hence is light and adapted to be moved about wherever its use is desired. In its action upon the pipes undergoing treatment, very satisfactory results may be obtained without affecting any threads that may be formed on the body of the pipe. Realizing, however, that the principles of this invention are susceptible of embodiment in forms other than the particular one shown and described herein, I desire that all such modifications or changes which are based either in whole or in part upon the improved features peculiar to this invention, should be included within the scope of this patent, as more definitely set forth in the claims following.

40 I claim:

1. In a pipe cleaning machine, the combination of a driving and two driven rollers arranged to receive between them a pipe for treatment, the three rollers having parallel axes and being of substantially the same length with the ends of the driven rollers coincident, the driving roller, however, being misaligned therewith, the acting surfaces of each roller being grooved circumferentially, substantially as described.

2. In a pipe cleaning machine, the combination of a driving and two driven rollers arranged to receive between them a pipe for treatment, the three rollers having parallel axes and being of substantially the same length with the ends of the driven rollers coincident, the driving roller, however, being misaligned therewith, substantially as described.

60 3. In a pipe cleaning machine, the combination of a driving roller and a plurality of driven rollers arranged to receive between all of them a pipe for treatment, the several

rollers having parallel axes and being of substantially the same length with the ends 65 of the driven rollers coincident, the driving roller being misaligned therewith, the acting surfaces of all the rollers being grooved circumferentially, substantially as described.

4. In a pipe cleaning machine, the combination of a driving and two driven rollers arranged to receive between them a pipe for treatment, the three rollers having parallel axes and being of substantially the same length with the ends of the driven rollers 70 coincident, the driving roller, however, being misaligned therewith, the acting surfaces of each roller being grooved circumferentially, that of the driving roller having cross cuts in addition, substantially as described. 80

5. In a pipe cleaning machine, the combination of a driving and two driven rollers arranged to receive between them a pipe for treatment, the three rollers having parallel axes and being of substantially the same 85 length with the ends of the driven rollers coincident, the driving roller, however, being misaligned therewith, the acting surfaces of each roller being square cut circumferentially to provide an annular groove, substantially as described. 90

6. In a pipe cleaning machine, the combination of a driving roller and a plurality of driven rollers arranged to receive between all of the rollers 95 having parallel axes with the forward ends of the driven rollers in a coincident plane, the corresponding end of the driving roller, however, being misaligned therewith, the acting surfaces of all the rollers being grooved circumferentially, substantially as described. 100

7. In a pipe cleaning machine, the combination of a driving and two driven rollers arranged to receive between them a pipe for treatment, the three rollers having parallel axes and being of substantially the same length with the ends of the driven rollers 105 coincident, the driving roller, however, being misaligned therewith, and means for moving one of the rollers upon the pipe with a 110 variable degree of pressure, substantially as described.

8. In a pipe cleaning machine, the combination of a driving roller and a plurality of driven rollers arranged to receive between 115 all of them a pipe for treatment, the several rollers having parallel axes and occupying longitudinal positions relative to each other tending to exert a tractive force upon the pipe whereby the pipe is caused, to travel 120 through the machine, substantially as described.

JOHN GROH.
